UNITED STATES PATENT OFFICE

2,574,667

STRUCTURAL SUPPORT FOR ROOFS
AND FLOORSEverett C. Shuman, Haddonfield, N. J., assignor
to Owens-Illinois Glass Company, a corpora-
tion of Ohio

Application May 23, 1947, Serial No. 750,029

4 Claims. (Cl. 189—34)

1

My invention relates to structural supporting means embodied in roof or floor constructions and more particularly to supporting members for tile roofs, floors and the like. The invention provides a novel form of sub-purlin providing a support for tiles used in such structures.

An object of the invention is to provide a supporting member or sub-purlin particularly adapted to support lightweight tile as for example, tile now on the market under the registered trade-mark name "Kaylo," such tile consisting of calcium silicate with or without reinforcing materials. The usual supporting bars or members commercially used for such purpose are heavy, uneconomical and otherwise unsuited for such structures. A feature of the present invention consists in providing a sub-purlin which, while of adequate strength and rigidity, is of such light weight per unit of length that mechanical handling is not necessary for usual applications.

A further object of the invention is to provide a structural member of the character indicated made of sheet metal and of a form adapted to be shaped from standard metal sheets.

A further object is to obtain an efficient distribution of the steel or sheet material having a high section modulus per unit of weight, combined with a low height.

A further object of the invention is to provide a sub-purlin adapted to be handled with ease, which will not crush in mechanical handling and which will not roll.

A further object is to provide a tile supporting structure which projects a comparatively short distance above the base or loading surface, thereby obtaining low thermal conductivity above the loading surface.

A further object attained by such construction consists in reducing to a minimum the tendency for moisture condensation in a high humidity.

A further object of the invention is to provide a supporting structure of the character indicated which is shaped and designed to serve as a conduit.

A further object of the invention is to provide a structure of the character indicated formed of sheet metal shaped to provide a web of double thickness having the web members welded at intervals in order to increase the rigidity of the structure and fortify it against bending or buckling when subjected to loading and lateral strains.

Other objects of the invention will appear hereinafter.

Referring to the accompanying drawings:

Fig. 1 is a cross-sectional elevation of a portion of a structure embodying my invention; and

2

Fig. 2 is a part-sectional end elevation, parts being broken away, of a modified form of rail or sub-purlin.

Referring to Fig. 1, I have shown a structure 9 built of tiles 10 supported on rails or sub-purlins 11. The structure 9 may be the same as illustrated and described in my co-pending application, S. N. 742,291, filed April 18, 1947, Structural Supporting Members for Roofs and Floors, now abandoned.

In the present invention, the sub-purlins 11 may be supported in the usual manner by purlins as shown for example, in said co-pending application.

The body of the sub-purlin or rail 11 as shown in Fig. 1, is in the form of a tube, rectangular in cross section, being substantially square with the corners 12 slightly rounded. It comprises a horizontal base 13, vertical sides 14, and a top including substantially horizontal supporting members 15 providing loading surfaces on which the ends of the tiles rest. The sub-purlin may be formed of standard plates of sheet metal rolled or bent into the shape illustrated.

Projecting upwardly from the top members 15 and extending lengthwise of the rail, are web portions 16 having their inner faces abutting to form a double ply anchorage web. The web is formed along its upper edge with outwardly and downwardly turned marginal flange portions 17. The sub-purlins may be of usual or any desired length and at intervals along the web 16, the two web members are rigidly and securely united as by spot welding 18.

The tiles 10, which may be made of calcium silicate or other light-weight material, may be arranged in rows between the rails and are directly supported on the top or flange portions 15. The adjacent ends of the tiles are spaced a short distance apart with spaces between the web 16 and the ends of the tiles. The space between the tiles is filled with grout 20 or a slurry of cementitious material which sets or hardens to form a rigid structure. The material 20 which is of low thermal conductivity provides good heat insulation and counteracts the tendency to moisture condensation due to temperature differentials between the metal structure and the atmosphere at the surface of the tile. The web 16 with its flange or hook portion 17 being embedded in the material 20, provides an anchor by which the tiles are securely held against being lifted out of place by wind storms or other forces. The body of the rail or sub-purlin, being hollow, is adapted to serve as a conduit for drainage or other purposes.

Fig. 2 illustrates a modified form of the sub-

purlin in which the rectangular body is of substantially less depth than width, the side walls 14' being of substantially less height than the width of the base 13. The upper marginal portions 17^a of the web 16 are formed by bending such marginal portions downward and then back on themselves.

Modifications may be resorted to within the spirit and scope of my invention.

I claim:

1. A rail adapted to form a sub-purlin in a building structure, said rail consisting of a single sheet of metal bent to form a rectangular hollow body comprising a horizontal bottom, vertical sides and a horizontal top, the top consisting of sections formed by bending the sheet material inwardly at the upper edges of said sides, the rail including a web extending lengthwise thereof midway between said sides and formed by bending the sheet material upwardly at the middle of said top, the web consisting of flat vertical sections having their inner faces in contact throughout to provide a two-ply web, the rail including upper marginal portions extended outwardly from the upper edges of said flat vertical sections 25 to form an anchor.

2. The rail defined in claim 1 wherein the plies of said web are spot-welded together at intervals along the web.

3. A rail adapted to form a sub-purlin in a 30 building structure, said rail consisting of a single sheet of metal comprising an intermediate portion bent to form a tubular body substantially rectangular in cross section and comprising a flat horizontal bottom, vertical sides and hori-

35 zontal top portions inturned from the sides, and integral web portions extending vertically upward from the inner edges of said inturned portions and having their inner faces in contact to form a two-ply web, said web terminating in outwardly turned marginal portions extending along the upper edge of the web and projecting outwardly beyond the web.

4. A rail adapted to form a sub-purlin in a building structure, said rail consisting of a single sheet of metal comprising an intermediate portion bent to form a tubular body substantially rectangular in cross section and comprising a flat horizontal bottom, vertical sides and horizontal top portions inturned from the sides, and integral web portions extending vertically upward from the inner edges of said inturned portions and having their inner faces in contact to form a two-ply web and terminating in outwardly turned marginal portions extending along the upper edge of the web and projecting outwardly beyond the web, the plies of said web being spot-welded together at intervals along the web.

EVERETT C. SHUMAN.
